UNITED STATES PATENT OFFICE.

BLUFORD HEAVNER AND CAREY A. MANKER, OF PEARL, ILLINOIS.

MEANS FOR PROTECTING SAFES FROM BURGLARS.

No. 866,929.

Specification of Letters Patent.

Patented Sept. 24, 1907.

Application filed April 16, 1906. Serial No. 311,949.

To all whom it may concern:

Be it known that we, BLUFORD HEAVNER and CAREY A. MANKER, citizens of the United States of America, and residents of Pearl, in the county of Pike and 5 State of Illinois, have invented certain new and useful Improvements in Means for Protecting Safes from Burglars, of which the following is a specification.

This invention relates to the use within a safe, of a volatile injurious chemical confined in a bottle or 10 other easily breakable receptacle.

The object of the invention is to locate such a chemical-containing receptacle within the safe in close proximity to the inner side of the outer door in such position that the breaking of the outer door by burglars 15 or otherwise will shatter said receptacle and allow the volatile contents thereof to fill the surrounding atmosphere. The vapors of said chemical so released being unbearable to breathe and injurious to the eyes, drives the burglar from his work and leaves the safe with its 20 inner door intact, thus protecting its contents. The burglar is afraid to return as the escaping chemical remains in the atmosphere for several hours after its release and is liable to attract the attention of the watchman or others and cause his discovery.

25 In the accompanying drawings, Figure 1 represents a perspective view of a safe with a portion thereof broken out to show the location of a chemical receptacle; and Fig. 2 represents a detail sectional view taken on line 2—2 of Fig. 1.

30 In the embodiment illustrated, a safe S of ordinary construction is provided with the usual outer door a, intermediate or jacket door b with the space d between them, and the inner door c with a space e between it and the intermediate door b, the interior of the safe

being shown at f. On the intermediate door b is shown 35 the usual handle j projecting into the space d. Suspended from this handle j by a cord or wire k is a pocket or bag k' in which is disposed a breakable bottle x containing a volatile injurious chemical.

In the use of this device when the chemical containing receptacle x is suspended in its pocket k from the handle j in the space adjacent the outer door, if a burglar attempts to break open the door by dynamiting or otherwise, the concussion occasioned by the explosion breaks the bottle x, releasing its contents which 45 quickly volatilizes and fills the surrounding air, rendering it impossible to breathe and thus compelling the burglar to cease from his work and flee and the air remains in this condition for several hours after the 50 breakage of the receptacle and the contents of the safe are thus protected.

I claim as my invention:—

1. A safe or vault having an inner door and an outer door, and means arranged in the space between said doors from which a pocket is suspended, and a breakable receptacle in said pocket containing a volatile injurious fluid. 55

2. The combination with a safe or the like having the usual inner, outer and intermediate doors, said intermediate door being spaced from the outer door and having a handle projecting into said space, a pocket suspended within said space from said handle, and a breakable receptacle in said pocket containing a volatile injurious fluid. 60

In testimony whereof we have signed our names to this 65 specification in the presence of two subscribing witnesses.

BLUFORD HEAVNER
CAREY A. MANKER.
